(57) **CLAIM**

The ornamental design for a drum pedal stabilizer as shown and described.

DESCRIPTION

FIG. 1 is a front, right and top perspective view of a drum pedal stabilizer, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a front and bottom perspective view of the drum pedal stabilizer in use.

The broken lines depict environmental structure that form no part of the claimed design.

The stippled shading in FIG. 3 represents a contrast in the surface material.

1 Claim, 8 Drawing Sheets
